UNITED STATES PATENT OFFICE.

WILLIAM H. ERMENTROUT, OF READING, PENNSYLVANIA.

STOCKING-TURNING MACHINE.

964,959.

Specification of Letters Patent. Patented July 19, 1910.

Application filed April 18, 1910. Serial No. 556,015.

To all whom it may concern:

Be it known that I, WILLIAM H. ERMENTROUT, citizen of the United States, residing at Reading, in the county of Berks and State of Pennsylvania, have invented certain new and useful Improvements in Stocking-Turning Machines, of which the following is a specification.

This invention relates to improvements in stocking turning machines and the object is to facilitate the turning of stockings during the process of manufacture. Ordinarily, when the stocking is "topped" it is on the so-called "wrong" side and it is customary to turn it by hand, which is a slow process.

My object in the present invention is to provide a device that will turn the stockings rapidly, and the invention consists of an exhaust fan, with a specially constructed fan, and having a funnel at the entrance to the fan casing, over which the stocking is slipped, and the stocking is drawn into the casing and turned while being so drawn, after which it is deposited through the exit tube.

The invention is more fully described in the following specification and clearly illustrated in the accompanying drawing, in which:—

Figure 1 is a front elevation of my machine, showing a stocking just ready to be turned and another being ejected therefrom. Fig. 2 is a vertical central sectional view of the machine, showing the fan construction. Fig. 3 is a front view of the fan, showing the screen.

The numeral 1 designates the casing. This is of substantially the ordinary exhaust fan construction, but I have shown my fan 2 provided with but four blades 5. This fan is mounted on the usual shaft 6 and is driven from the pulley 7 by any suitable power.

To the front of the fan, I secure a cover in disk form, 8, made of a suitable screen of comparatively large or coarse mesh. This cover is of the same diameter as the distance across the fan, and thus covers the blades entirely.

The numeral 9 indicates the inlet to the

casing and this inlet is provided with a funnel 10.

The contracted end 11 of the funnel is of uniform tubular construction, and adapted to receive the top or open end of a stocking by having the stocking slipped over the said end as shown in Fig. 1.

The numeral 12 indicates the outlet from the casing and this I prefer to form, as shown, as an elbow, to prevent the stockings being thrown to points other than the proper receptacle provided therefor.

When it is desired to operate the device, the stocking is slipped over the end of the tubular portion of the funnel, just sufficiently to engage it from falling, and while being so placed, it is necessarily held by the hand of the operator at that point and this will permit the end or foot portion to be drawn into the tube 11, and the release of the stocking by the operator will permit the entire stocking to pass into the casing, having been turned during and by reason of the process of entering it.

The casing is larger internally than the diameter of the fan, and when the stocking is drawn into the casing, it will strike the screen disk which covers the blades, thus preventing it from becoming entangled therewith; the centrifugal force of the fan will throw the stocking toward the inner wall of the casing, and it will pass out of the exit tube 12 at the bottom.

Having thus fully described my invention, what I claim and desire to secure by Letters Patent is:—

1. In a stocking turning machine a casing, a revolving fan located therein, a screen covering the face of said fan, said casing having an inlet; a funnel secured to said inlet adapted to receive a stocking and turn it while being drawn into the casing by the action of the fan.

2. In a stocking turning machine, a casing, a fan located therein, a perforated cover for said fan, and a tube leading to the face of said fan adapted to engage and hold a stocking while the action of said fan turns it and draws it into the casing.

3. In a stocking turning machine, a casing having inlet and outlet openings, a re-

volving fan located therein; a screen disk secured to the face of the fan and entirely covering the blades, a funnel secured to the inlet, a tube of uniform diameter formed on the funnel, adapted to receive the open end of a stocking and hold it while being turned and drawn into the tube by the action of the fan; and an elbow secured to the outlet.

In testimony whereof I affix my signature, in presence of two witnesses.

WILLIAM H. ERMENTROUT.
